DESIGN FOR A COMBINED GRAB BAR AND SOAP TRAY

Jesse D. Vail, Chicago, Ill., assignor to Gardner-Vail Inc., Chicago, Ill., a corporation of Illinois

Application March 7, 1935, Serial No. 55,765

Term of patent 14 years

To all whom it may concern:

Be it known that I, Jesse D. Vail, a citizen of the United States, residing in Chicago, in the county of Cook and State of Illinois, have invented a new, original, and ornamental Design for a Combined Grab Bar and Soap Tray, of which the following is a specification, reference being had to the accompanying drawing, forming part thereof.

Figure 1 is a perspective view of a combined grab bar and soap tray showing my new design;

I claim:

The ornamental design for a combined grab bar and soap tray, substantially as shown.

JESSE D. VAIL.
